UNITED STATES PATENT OFFICE.

WALTER WRIGHT, OF NEW YORK, N. Y.

ROTARY TYPE-SUPPLY DRUM.

1,226,046.

Specification of Letters Patent. Patented May 15, 1917.

Application filed March 10, 1909, Serial No. 482,530. Renewed October 6, 1916. Serial No. 124,206.

To all whom it may concern:

Be it known that I, WALTER WRIGHT, a citizen of the United States, residing at New York, State of New York, have invented new and useful Improvements in Rotary Type-Supply Drums, of which the following is a specification.

This invention relates to a rotary type supply drum, or magazine for carrying a quantity of grooved type, loosely slideable in channels therein, together with a holder suitable for receiving type from said magazine, so that when placed therein an impression may be taken from the face of said type, 15 when said holder is placed in, and used in connection with a machine constructed for that purpose.

The object of the invention is to provide an apparatus of this character simple in 20 construction and capable of being used with great speed and accuracy for setting up type in name and address holders, which may be done by sliding type from the channels of the type drum into corresponding channels 25 in a holder, by the use of a pointed stick or other suitable instrument, such holder being adapted for use in connection with a machine for printing the names and addresses on the headings of typewritten letters, when 30 it is desirable to send the same letter, or subject matter, to a number of different firms or individuals, as is customary in circularizing, and also for printing such names and addresses on cards, for card indexes, or upon 35 statements, envelopes and similar purposes.

The object of the invention however is understood not to be limited in its use to these particular purposes, as any suitable member for holding type, and receiving it 40 from the different channels of the type drum, from which a printed impression could be taken when placed in a machine for that purpose, may be substituted for the holder here shown, as will be readily understood from the drawings and description 45 here given.

Figure 1, is a side elevation of my apparatus partly in section. Fig. 2, is an end view of same, parts of which are broken 50 away.

Referring to the drawings, 1 indicates a metal base from which extend supports 2, for a shaft 3, which rotates in bearings 4, in the upper ends of said supports. To said 55 shaft is secured by screws, the hubs 5, of a type drum 6, so as to rotate therewith. Said

type drum is composed of end supports 7, which extend from the hubs 5, to the rims 8, upon which are supported ribs or rails 9' which extend longitudinally across the drum 60 from one rim to the other. The said rails 9' are set a short distance apart so as to form grooves or type channels 9, between said rails, and in which are slidably carried, 65 grooved type 10. The shaft 3, extends beyond the end of the type drum on the left, and has secured thereto, and rotating therewith, an index wheel 12, which is of the same diameter as the type drum, and similar in construction to the ends thereof. Said 70 index wheel 12, has on its upper side or face, a character index 14, and attached to one of the supports 7^a of said index wheel, is a shaft 15, on which as will be hereafter explained, is loosely mounted a handle 16. Mounted 75 on said shaft 15 and slideable longitudinally thereon is a sleeve 13, to the inner side of which is secured a centering and locking pin 19, the right end of which is located in, and slideable through, a hole 17 in one of the supports 7 of the index wheel. The movement of the handle 16, and therefore also of the sleeve 13 to the right, causes the pin 19 to enter any one of a series of holes 20, in the stationary locking plate 21, which is supported by rods 21^a, and when said handle 16, and therefore with it the sleeve 13 and the locking pin 19, are moved on the shaft 15, to the left, the locking pin will be withdrawn 80 from the hole 20 far enough to the left to 90 remove it out of contact with the locking plate 21, so that it may, together with the index wheel and type drum, be rotated without coming in contact with any of the holes of the locking plate. When it is again de- 95 sired to lock the drum from further rotation, this can be done by pressing the handle to the right against the pressure of the spring 18 so that the centering or locking pin 19 will again enter any one of the holes 20 of 100 the locking plate 21, which is at that time opposite thereto, thus again locking the drum from further rotation until the pin 19 is again withdrawn by sliding the handle 16 to the left, in which position it is normally 105 held by the pressure of the spring 18.

On a frame 22, supported by an upward extension 23, from the support 2 on the left, is slideably supported in undercut grooves 24, a carriage 25, in which there is removably carried a holder 26, in which are longitudinal type channels 27. Said holder is 110

locked in said carriage on its lower side by a projection or lip 28, and on its upper side by a tongue 29, of a lever 30 pivoted on said carriage at 31. Said carriage 25, may be 5 locked in any one of several positions against upward or downward movement by a V-shaped spring 33, which meshes in any one of a series of V-shaped recesses 34, on the bottom of said carriage. The said carriage 10 25 however, may be moved upward or downward by overcoming the pressure of said spring, and thus raising its end out of any one of said recesses 34, but when said spring is centered in any one of said recesses, one 15 of the type channels 27 of the holder, will then be in alinement with one of the type channels 9 of the type drum, if said drum is at that time locked against further rotation by the locking pin 19 then being in one 20 of the holes 20 in the locking plate 21, and when the holder 26 and the type drum 6 are in such positions, the type 10 may, by sliding the same with a pointed stick or any other suitable instrument be moved from a 25 type channel 9 of the type drum, into one of the type channels 27, of the name and address holder.

As there are as many holes 19 in the locking plate 21, as there are type channels in 30 the type drum, any one of said type channels may be locked opposite to a fixed pointer 35, secured to the locking plate 21; therefore by using each type channel of the type drum for a different character or type, 35 and by placing a cut or impression of such characters on the index 14, directly opposite to the type channels in which the different type are carried, then by rotating said type drum until the pointer 35 is directly opposite to the desired character on said index, if the type drum is then locked at that 40 point, by the locking pin 19, the type channel of the type drum containing type of the same character as that shown on the index 45 directly opposite to the said pointer, will then be in alinement with a type channel 27 of the holder 26, so that one or more of such type may then be moved from the channel of the type drum, into a type channel of the 50 holder, and this operation may be repeated until all the type of different characters desired, have been moved from the different channels of the type drum into one of the channels of the holder 26, for the purpose 55 of setting up a name and address, or other type faced matter therein.

From the frame 22 extends an arm 36, on which is adjustably supported an arm rest 37, on a shaft 38 threaded at its lower end so that by turning said shaft, the arm rest 37 may be raised or lowered to suit the convenience of the user.

On the left side of the type drum, there is provided a stationary guard plate 39 supported from the base 1, and which fits close

to the ends of the type channels of the type drum for the purpose of preventing the removal of the type therefrom, except at the point 40 where said plate is cut away a sufficient distance to allow the upward or downward movement of the holder, so that any one of the type channels thereof, to be brought into alinement with any one of the type channels of the type drum, so that the ends of the type channels of the type drum, 70 will fit closely up against the end of a type channel of the holder, and thus make one continuous type channel in both the holder and type drum, so that type may be moved out of a channel in either into a channel into 75 the other without passing through any intermediate part. On the right end of said type drum, the rim 8 is extended upward past the ends of the type channels 9, thus preventing the removal of type from the 80 channels at that end of the drum. 85

The distance from one type channel to another, in the holder 26, may be varied to suit conditions, by having the undercut recesses 34 on the carriage 25, placed nearer 90 to each other, or farther apart from each other, thus varying the distance of one line of type from another, or one type channel from the other, and this change can be made in connection with the holder and carriage, 95 without the necessity of changing in any detail the construction of the type drum, the position of the type channels in said drum, or interfering in any manner with the index, centering or locking pin, or any other part 100 of the construction.

The channels in the holder 26, in which it is usually necessary to economize room, may be placed more closely together than the channels in the drum 6, as shown. The ends 105 of the holder 26 close those channels in the drum 6, which are next above and below the channel from which type is being transferred. Moreover, there is no liability of the operator making a mistake through having 110 more than one channel in the type drum registering with channels in the holder 26.

I claim:

1. In an apparatus of the character described, the combination of a frame, a type drum, channels on said drum for carrying grooved type, an index with characters displayed thereon, type in said channels corresponding to the characters displayed on said index opposite thereto, a pointer, a type holder having a series of longitudinal type channels therein, said holder being supported on the frame between said type drum, and said index, a handle for rotating said drum and index in unison, and means associated with said handle for locking said drum and index, so that any one of the channels of the type drum may be locked in alinement with one of the channels of the holder, substantially as described. 115 120 125 130

2. In an apparatus of the character described, the combination of a frame, a type drum, type channels in said drum for carrying grooved type capable of sliding therein, a character index having a character displayed thereon opposite to one of said type channels, a stationary pointer supported on said frame, a type holder having type channels therein corresponding with the channels in said drum, said holder being supported from the frame, a handle for rotating said drum and index, and means associated with said handle for locking said drum and index when any character displayed on said index is opposite to said pointer, and means whereby one of the channels of said holder will be in alinement with the channel of the drum carrying type of the same character as that displayed on said index opposite to said pointer, when so locked, so that type may be moved from said drum, into one of the channels of the holder, substantially as described.

3. In an apparatus of the character described, the combination of a frame, a type drum, type channels on said drum for carrying grooved type, a character index having characters displayed thereon opposite to said channels, a stationary pointer, a type holder having channels therein suitable for holding grooved type, means for supporting said holder, a handle for rotating said drum, and means associated with said handle for locking said drum from further rotation when any character on the index plate is opposite to said pointer, a carriage for adjustably supporting said holder, and means whereby any one of the type channels in said holder may be brought into alinement with the end of the type channel on said drum, containing type of the same character as that displayed on said index, opposite to said pointer, substantially as described.

4. In an apparatus of the character described, the combination of a frame, a type drum, type carried on said drum, a character index rotatable therewith, a pointer, a type holder, a carriage for supporting said holder, means whereby said carriage may be raised or lowered so that any one of the type channels therein may be brought into alinement with any one of the channels of the type drum, a handle for rotating said drum, and means associated with said handle for locking said drum when any one of its channels is in alinement with the end of one of the channels of said holder, substantially as described.

5. In an apparatus of the character described, the combination of a frame, a type drum, type channels on said drum for carrying grooved type, grooved type in said channels capable of being moved longitudinally in said channels, a character index

having characters displayed thereon to correspond with the type carried in the different channels of said drum, a pointer, a type form holder having longitudinal type channels therein, a carriage for supporting said holder, means through the movement of said carriage for bringing any one of the type channels of said holder into alinement with any desired channel of the type drum, a handle and means associated with said handle for locking any type channel of said drum, opposite to a channel of said type form holder, substantially as described.

6. In an apparatus of the character described, the combination of a frame, a type drum, type carried thereby, a character index, a pointer, means supported on said frame between said drum and index for receiving type from said drum, means for rotating said drum and index in unison, and means associated with said rotating means for locking said drum, so that type of any desired character may be removed from said drum into said receiving means, substantially as described.

7. In an apparatus of the character described, the combination of a frame, movable means for carrying grooved type, an index movable therewith, a type holder supported on said frame between said index and type carrying means, type channels in said holder and in said type carrying means, the distance between the channels in said holder being different from the distance between said channels in the type carrying means, and means associated with said holder whereby any one of its channels may be brought into alinement with any one of the type channels on said type carrying means, substantially as described.

8. In combination with a frame and a type magazine mounted to revolve on a horizontal axis therein, said magazine having open ended type channels, of a stationary guard for closing the ends of the channels, said guard having a recess, a movable type holder adapted to project into the recess, said holder holding a plurality of type channels, a support for detachably receiving said type holder and means for alining any of the type channels of the magazine with one of the type channels of the said type holder.

9. The combination of a revoluble type magazine having type channels open at their ends, a stationary guard plate to close the ends of said channels, said guard plate having an opening, and a support for detachably receiving a type holder in position to occupy the recess in said guard plate, the holder having type channels set at intervals disagreeing with those in the magazine.

10. The combination with a horizontally disposed movable type magazine provided with type channels, a support at one end of

the magazine for receiving a type holder, of a multiple channeled type holder adjustably mounted on said support and a stationary guard forming a closure for the type channels of the magazine, said guard having an opening with which any of the channels of the holder may register and into which said holder is movable.

11. The combination with a rotary type magazine having a plurality of open ended channels and an index designating the characters in each channel, of a grooved support intermediate said magazine and said index, a type holder movable transversely on said support and means whereby its channels are registerable with said index and with a corresponding channel in said magazine.

12. The combination with a rotary type magazine having horizontally disposed channels spaced about its periphery, of a type holder slidably mounted tangentially to the periphery of said magazine, said holder having a plurality of channels differently spaced from those of the magazine and means whereby any groove in said holder may be brought into intimate contact with any groove in said magazine.

13. The combination with a cylindrical type magazine and a frame in which it may rotate, of a flat type holder adapted to receive type from said magazine, a slide in which said holder may move longitudinally and a support for said slide, said slide being movable laterally of the channels in said type holder and being directly engageable therewith.

14. The combination with a cylindrical type magazine having open ended channels, of an apertured closure for the channels, a type holder having channels registerable with the magazine channels, through the aperture, a slide upon which said type holder is removably engaged, means for clamping said holder in said slide and means for moving said slide laterally of the channels.

15. The combination with a revoluble magazine carrying a supply of type arranged in rows horizontally on its periphery and a chase supported adjacent to one end of said magazine and movable transversely thereto, of means for indexing and rotating said magazine and means whereby said chase may be moved linearly into such relation with said magazine as to receive or deliver type directly to or from any alined row of type therein.

16. The combination with a revoluble magazine carrying a supply of type arranged in rows horizontally on its periphery, of a chase supported at one end of said magazine and movable transversely thereto, means for indexing and rotating said magazine, means whereby said chase may be moved linearly into such relation with said magazine as to receive or deliver type directly to or from any alined row of type therein, and means for preventing the escape of type from any other row of said magazine.

17. The combination with a type magazine having uniformly spaced open channels and means for preventing the extension of type except at a predetermined point, of a movable type holder having channels therein spaced differently from the channels of the said magazine, each of the channels being registerable with any of the magazine channels and capable of interchanging type directly therewith either to or from.

18. The combination in a typesetter, with a revoluble cylinder having longitudinal type grooves and mounted to rotate upon a horizontal axis, of a type holder provided with a plurality of grooves adapted to receive type, a support at one end of said cylinder and a slide movable in said support operable at a tangent to said cylinder and carrying said holder in such manner that any of its grooves may be placed in register with one of the grooves in said cylinder.

19. The combination in a typesetter, with a revoluble cylinder having longitudinal type grooves and mounted to rotate upon a horizontal axis, of a type holder provided with a plurality of grooves adapted to receive type, a support at one end of said cylinder, a slide movable in said support operable at a tangent to said cylinder and carrying said holder in such manner that any of its grooves may be placed in register with one of the grooves in said cylinder, means for rotating said cylinder, an index therefor, and a locking means whereby said cylinder may be held in any desired registration.

In testimony whereof I have hereunto set my hand in the presence of two subscribing witnesses.

WALTER WRIGHT.
